United States Patent Office.

ELIAS INGRAHAM, OF BRISTOL, CONNECTICUT.

Design No. 3,850, dated February 15, 1870.

DESIGN FOR CLOCK-CASE.

The Schedule referred to in these Letters Patent and making part of the same.

To all whom it may concern:

Be it known that I, ELIAS INGRAHAM, of Bristol, county of Hartford, and State of Connecticut, have invented or produced a new and original Design or Pattern for a Clock or Time-Keeper Case; and to enable others skilled in the art to produce the same, I will proceed to describe, referring to the photographic drawing, in which the same letters indicate like parts in each of the figures.

In the accompanying photographic drawings is shown a new and original design or pattern for a clock or time-keeper case.

Figure 1 is a front elevation thereof.

Figure 2 is an edge view.

a is the case proper.

b is a door or sash.

c are rounded elevations or projections.

d are curved depressions.

e is a plain door or sash moulding.

f is a time-indicating dial.

The whole is arranged to produce a plain rich sign or pattern for a clock or time-keeper case.

What I claim, and wish to secure by Letters Patent, is—

A new and original design or pattern for a clock or time-keeper case, substantially as shown and set forth.
